Primary Examiner — Anhdao Doan(74) Attorney, Agent, or Firm — NZ Carr Law Office(57) CLAIM

We claim the ornamental design for a saliva test device, as shown and described.

DESCRIPTION

FIG. 1 is a top view of a saliva test device of our design;
FIG. 2 is a bottom view thereof;
FIG. 3 is a right side view thereof;
FIG. 4 is a left side view thereof;
FIG. 5 is a front view thereof;
FIG. 6 is a rear view thereof;
FIG. 7 is a top rear perspective view thereof; and,
FIG. 8 is a front bottom perspective view thereof.
